UNITED STATES PATENT OFFICE.

JULIA S. HOTCHKISS, OF NORWALK, CONNECTICUT.

STAPLE-DRIVING MACHINE.

Application filed August 17, 1922. Serial No. 582,365.

To all whom it may concern:

Be it known that I, JULIA S. HOTCHKISS, a citizen of the United States, residing at Norwalk, county of Fairfield, State of Connecticut, have invented an Improvement in Staple-Driving Machines, of which the following is a specification.

This invention relates to stapling machines and particularly to that type known as strip stapling machines wherein each staple is severed from a strip of integrally connected staples and then driven, the staple strip being fed forwardly at each operation of the machine to bring the staples successively into a position to be severed and driven.

The invention has for an object to provide an improved feeding mechanism for the staple strip and one in which, when the feeding element which engages the strip is retracted to its rearward position to engage the strip prior to advancing the same, it will be removed from engagement with the strip and so will have no tendency to move the strip backwardly, and a separate hold-back will, therefore, be unnecessary.

It is a further object of the invention to provide an improved feeding mechanism for a staple strip which will also straighten the individual staple should it be bent out of position, and thus prevent clogging of the machine.

With the foregoing and other objects in view I have devised the improved stapling machine illustrated in the accompanying drawing, in which—

Fig. 1 is a sectional elevation through the body of the machine showing the elements of the device in position ready for a staple driving operation.

Fig. 2 is a similar view showing the position of the elements at about the time the points of the staple being driven is to enter the work.

Fig. 3 is a similar view showing the elements in the position they occupy after the staple has been driven but before they move to the position shown in Fig. 1.

Fig. 4 is a partial transverse section substantially on the line 4—4 of Fig. 1, and

Fig. 5 is a detailed partial plan view of the staple engaging means of the feeding mechanism on an enlarged scale and showing it in staple engaging position.

The machine comprises the base 10 supported on suitable rubber or other supports

11 and provided with ears 12 between which the staple strip carrying bar or slide 13 is pivoted by any suitable means, such as a pin 14. This slide is secured within the lower part or body of casing 15 by any suitable means such as transversely extending pins 16. At the forward part of the body or casing is the vertically reciprocating plunger 17 provided with lateral longitudinal guide ribs 18 adapted to slide in vertical grooves 19 in the casing to properly guide the plunger. The lower end of the plunger extends horizontally as shown at 20 providing a sharp edge 21 cooperating with the forward edge 22 of the slide to sever the staples and clinch the same in coaction with the anvil 10' when the plunger is reciprocated in the usual manner employed in this type of machines. The strip 23 is inserted on the top of the rail or slide from the rear end thereof in the usual manner.

Within the chamber 24 in the casing or body 15 is mounted my improved feeding mechanism which comprises a block 25 mounted to reciprocate horizontally in the casing on any suitable means, such as pins 26 extending transversely of the casing. This block is provided with a downwardly projecting portion 27 at its rear end to which the bell crank lever 28 is pivoted by any suitable means such as a pin 29, this bell crank being provided with upright and lateral arms 30 and 31 respectively upon opposite sides of the sliding block 25, the laterally or substantially horizontally extending arms 31 being connected at their lower edges by a bridge member 32. Adjacent the forward ends of the horizontally extending arms 31 are means for engaging the individual staples comprising substantially U-shaped members 33 the upright legs 34 of which are adapted to extend on opposite sides of the prongs of the staple as shown in Fig. 5. A spring 35 is mounted between the sliding block 25 and the bridge member 32 and tends to hold the U-shaped member 33 in the lowermost or staple engaging position, the rearward portion of the slide being narrowed on each side an amount equal to the thickness of the upright arms 30 to provide stop shoulders 36 adapted to be engaged by the forward edges of these arms to limit the downward movement of the U-shaped members.

Pivoted between the upright arms 30 adjacent the upper end thereof by a suitable

pivot pin 37 is a pawl 38 provided with an inclined forward end 39 adapted to lie in the path of movement of the inclined surface 40 on the lug 41 carried by the plunger 17. 5 The upper portion of the end of the block 25 is also inclined as shown at 42 so as to be engaged by this same lug whereby the block may be reciprocated in a manner presently to be described. The block is provided with 10 a socket 43 leading from the rear end thereof within which is placed a coil spring 44 bearing at its opposite ends on the bottom of this socket and the vertically extending wall 45 of the casing 15, this spring tending 15 to hold the block in its forward position as shown in Figs. 1 and 2. The block is provided on its upper edge with a longitudinally extending recess 46 into which the pawl 38 may rest as shown in Figs. 1 and 20 3. A very light spring 47 carried by the upright arms 30 tends to hold the pawl 38 against the block 25. This spring is merely strong enough to prevent the pawl moving away from the block should the machine be 25 turned upside down.

The plunger, after a clinching operation, is moved to its uppermost position as shown in Fig. 1 by means of a spring 48 surrounding the upper portion thereof and abutting 30 at its opposite ends on the top of the casing and the underside of the hand piece or cap 49, the upper movement of the plunger being limited by a suitable stop such as a transverse pin 50 carried by the casing in 35 alignment with the upper side of the lug 41.

The operation is as follows:

Assuming the parts are in the position shown in Fig. 1, a blow is struck with the hand on the cap 49 moving the plunger 40 downwardly. As this plunger moves downwardly the inclined surface 40 of the lug 41 engages the forward end 39 of the pawl 38 moving the same rearwardly and swinging the bell crank lever 28 about its pivot 29 45 to the position shown in Fig. 2 with the U-shaped staple engaging elements 33 raised above the top of the staple strip as shown in Fig. 2. During this part of the movement of the plunger the block 25 will remain in 50 its forward position as the spring 44 is stronger than the spring 35. Upon further movement of the plunger the inclined surface 40 of the lug reacts with the inclined surface 42 at the forward end of the block 55 25 and moves this block rearwardly to the position shown in Fig. 3 which carries therewith the bell crank lever 28. As the plunger reaches this lowermost position the block 25 reaches its rearward position shown in Fig. 60 3, and the forward end of the pawl 38 slides over the top of the lug 40 allowing the staple engaging elements 33 to move downwardly under the action of the spring 35 and engage the next adjacent rearward staple, as shown in Fig. 3. When the plunger 65

is released it will be moved upwardly under the action of the spring 48 allowing the spring 44 to move the block 25 and the bell crank lever 28 with the staple engaging elements 33 to the forward position, which will also carry forward therewith the staple strip to the position shown in Fig. 1, and bring the next staple in position to be operated on by the plunger upon its next downward movement. As the plunger moves upwardly 70 the forward end of the pawl 38 is raised by the top of the lug 40 until the same may drop by this lug to its position on top of the block 25, this action being shown by the dotted line position of this pawl indicated 75 in Fig. 1.

It will be apparent from the foregoing description that before the staple engaging elements of the feeding mechanism is given its rearward movement in its feeding cycle, they 80 are first moved from engagement with the staple strip and they are then moved backwardly in the reverse movement of the cycle while entirely free from the staple strip and so have no tendency to move the same backwardly and, therefore, with this feed no hold-back is required. After these elements 85 reach their extreme rearward position they are moved into engagement with the next rearwardly positioned staple and are then 90 moved forwardly to advance the strip the distance corresponding to the distance between the individual staples. If a staple happens to be bent rearwardly for example the foremost staple will engage the side of 95 the guiding means 19 and further movement of the feeding mechanism under the action of the spring 44 will straighten the staple by moving the prongs or legs thereof to the vertical or proper position. 100

Having thus described the nature of my invention, what I claim is:

1. In a strip staple machine having a movable plunger for severing and clinching the individual staples, in combination, staple strip feeding mechanism comprising means for engaging the strip, means for removing the engaging means from the strip, means for moving the engaging means rearwardly and then allowing it to again engage the staple strip, and means for then moving the engaging means forwardly to advance the staple strip; and means operated by the plunger for operating said feeding mechanism. 110

2. In a strip staple machine having a movable plunger for severing and clinching the individual staples, in combination, staple strip feeding mechanism comprising means for engaging a staple on said strip, means for raising said engaging means above the strip, means for then moving the engaging means rearwardly and allowing the same to engage the next adjacent staple, and means for then moving the engaging means 115 120 125 130

forwardly to advance the strip; and means operated by the plunger for operating said feeding mechanism.

3. In a strip staple machine having a movable plunger for severing and clinching the individual staples, in combination, staple strip feeding mechanism comprising means for engaging the strip, and means for removing the engaging means from the strip, moving it rearwardly, allowing it again to engage the strip and then moving it forwardly to advance the strip; and means operated by the plunger for operating said feeding mechanism.

15 4. In a strip staple machine having a reciprocating plunger for severing and clinching the individual staples, in combination, staple strip feeding means comprising a reciprocally mounted block, staple strip engaging means mounted on the block, coacting means carried by the plunger and strip engaging means to remove said latter means from engagement with the strip, coacting means on the plunger and block 20 adapted to then move the block rearwardly and allow the strip engaging means to move into engagement with the strip, and means for then moving the block forwardly to 25 advance the strip.

30 5. In a strip staple machine having means for severing and clinching the individual staples, in combination, staple strip feeding means comprising a reciprocable element, staple strip engaging means pivoted to said element, a pawl carried by said pivoted means, means operated with the first mentioned means adapted to coact with the pawl to remove the engaging means from the strip and then move the reciprocable 35 element rearwardly, said means also adapted to then release the pawl to allow the strip engaging means to engage the strip, and means for moving the reciprocable element forwardly to advance the strip.

40 45 6. In a strip staple machine having a reciprocating plunger for severing and clinching the individual staples, in com-

bination, staple strip feeding means comprising a bodily movable block, a lever pivoted to the block having staple strip 50 engaging means, a pawl pivoted to the lever, means carried by the plunger adapted upon reciprocation thereof to engage the pawl to swing the lever on its pivot and remove it from engagement with the strip, said means also adapted to then move the block rearwardly and release the pawl to allow the lever to engage the strip, and a spring adapted to move the block forwardly to 55 advance the strip upon upward movement of the plunger.

7. In a strip staple machine having a reciprocating plunger for severing and clinching the individual staples, in combination, staple strip feeding means comprising a bodily movable block, a lever pivoted to the block, means carried by the lever adapted to engage the prongs of the individual staples, a pawl carried by said lever, a spring tending to move the lever 70 to staple engaging position, a stronger spring tending to move the block to its forward position, and means carried by the plunger adapted to engage the pawl to swing the lever from engagement with the 75 strip, said means also adapted to then move the block rearwardly and allow the lever to engage a staple.

8. In a strip staple machine having a movable plunger for severing and clinching 80 the individual staples, in combination, staple strip feeding means comprising a movable element, means to engage the staple strip, said means being connected with said element and adapted for movement independently thereof, means operated by the plunger for imparting said independent movement to the strip engaging means and for imparting rearward movement to said 85 element, and means for advancing said 90 element.

In testimony whereof I affix my signature.

JULIA S. HOTCHKISS.
